UNITED STATES PATENT OFFICE.

THOMAS WILSON AND ARCHIBALD WILSON, OF DOAGH, IRELAND.

SUPPORT FOR BOBBINS, COPS, PIRNS, OR THE LIKE, WHEN UNWINDING THREAD, YARN, OR THE LIKE THEREFROM.

Application filed September 29, 1924. Serial No. 740,645.

To all whom it may concern:

Be it known that we, THOMAS WILSON and ARCHIBALD WILSON, both of The Villa, Doagh, county Antrim, Ireland, and both

5 subjects of the King of Great Britain and Ireland, have invented certain new and useful Improvements Relating to Supports for Bobbins, Cops, Pirns, or the like, When Unwinding Thread, Yarn, or the like Therefrom, of which the following is a specification.

This invention relates to supports for bobbins, cops, pirns, and the like, which turn on non-rotating spindles whilst the thread, 15 yarn or the like is being taken off. Heretofore it has been proposed to mount the bobbin, or the like, on a carrier which is pivoted below the base of the bobbin and is counter-weighted, the bobbin being free to 20 oscillate on the pivot and to relieve the tension of the yarn or thread while it is being wound off the bobbin.

The object of this invention is to provide a new support for bobbins comprising a 25 fixed member or bracket, a second member pivotally mounted on the fixed member and a bobbin carrier on the second member, the pivot pins being disposed so that they will be at right angles to the axis of the bobbin 30 carrier, the arrangement being such that whilst the bobbin can oscillate to suit the changing angle of the thread or yarn and relieve the tension thereof while the same is being wound off the bobbin or the like, 35 yet no counter-balancing extensions or weights are required.

The pivotal centres of the second member are arranged above the base of the bobbin and preferably either above the bobbin 40 itself or between the ends thereof, the pivotal axis, in all cases, being transverse to the axis of the bobbin carrier. In certain cases, where horizontal bobbins are used, the same may be located on a spindle or 45 carrier in a second member carried by a fixed bracket whose pivots have their common axis arranged transversely to the axis of the bobbin so that the second member with the bobbin thereon can accommodate 50 itself to the changing angle of the yarn or thread as it is wound off the bobbin.

The accompanying drawings illustrate, 55 simply by way of example, the invention as applied to the support for a wooden bobbin.

Fig. 1 is a side elevation of the bobbin and its support.

Fig. 2 is a front elevation corresponding to Fig. 1.

Fig. 3 shows an arrangement in which the 60 pivotal axis is above the bobbin.

Fig. 4 shows, in elevation, the bobbin arranged horizontally, in the pivotal member 3.

Referring to the drawings: 65

The bobbin carrier 1 is carried on a spindle 2 removably fitted on a member 3 which is pivotally mounted at 4 and 5 on a fixed bracket or support 6 on the machine frame 10, the axis through the pivots 70 4 and 5 being, in the example shown at Figs. 1 and 2, above the base of the bobbin and transverse to the axis of the bobbin.

As will be seen at Fig. 1 the bracket 6 75 has slots 11 therein and the pivot pins 4, 5, of the member 3 are entered into said slots. Alternately the member 6 may be provided with pivots adapted to enter and move freely in slots in the member 3. The member 3 can be readily removed.

In the example shown at Fig. 3 the pivots 4' and 5' are above the top of the bobbin with their common axis transverse to the axis of the bobbin. 85

In the example shown at Fig. 4 the bracket 6 is suitably supported on the machine frame 10, the member 3' being vertical and the bobbin lying horizontally, the axis through the pivots 4 and 5 being transverse 90 to the axis of the bobbin and between the ends thereof.

As the yarn or thread is wound off the bobbin, the latter is free to oscillate about the pivots 4, 5, as indicated in dotted lines, 95 Fig. 1, and the location of the pivots above the base of the bobbin, causes the latter, with its carrier 2, and supporting member 3, to act as a counterbalance to the pull of the yarn or thread whereby a constant tension on the yarn or thread is maintained without the necessity for employing counter-balancing weights or levers. 100

It is important, for the class of bobbin shown at Figs. 1 and 2, that the angle at 105 which the thread is drawn off should always be such as to prevent the thread rubbing and being chafed on the edge 7a of the bobbin, and also to avoid excessive drag on the thread through such contact, 110

and to avoid this a stop 8 is provided which limits the backward tilt of the bobbin, the forward tilt of the bobbin being preferably limited by a stop 9. The stop 8 also ensures 5 that the bobbin spindle or carrier will lie at a convenient angle for the operator placing a bobbin thereon, or for removing a bobbin therefrom, when required.

In the arrangement, Fig. 4, the horizontal 10 bobbin 7 is free to oscillate, along with the member 3, about the pivots 4, 5 of the bracket 6 which is shown broken off. It is obvious that as the yarn or thread is wound off from end to end of the bobbin, the 15 pivotal support can accommodate itself thereto.

It is of course to be understood that the constructions herein described are illustrative embodiments of the invention and that 20 various changes and modifications of the details of structure within the scope of the appended claims are to be considered within the spirit of the present invention.

Having now fully described our invention 25 we declare that what we claim and desire to secure by Letters Patent is:—

1. A bobbin or like support comprising a fixed member, a second member pivotally mounted on the fixed member and a bobbin 30 carrier on the second member, the pivotal axis of the second member being between the base and the top of the bobbin and at right angles to the axis of the bobbin carrier.

2. A bobbin or like support comprising a 35 fixed member with slots therein, a second

member with pivots thereon adapted to enter and move freely in said slots, a bobbin carrier on the second member, the pivotal axis of the second member being between the base and the top of the bobbin 40 and at right angles to the axis of the bobbin carrier.

3. A bobbin or like support comprising a fixed member with slots therein, a second member with pivots thereon adapted to 45 enter and move freely in said slots, the second member having a cross bar arranged below the pivots and carrying a spindle for the bobbin, the axis of said spindle being transverse to the axis of the pivots of the 50 second member.

4. A bobbin or like support comprising a U-shaped fixed member, a second U-shaped member pivotally mounted on the fixed member and a bobbin carrier on the second member, the pivotal axis of the second member being at right angles to the axis of the bobbin carrier. 55

5. A bobbin or like support, comprising a U-shaped fixed member, a second member in 60 the form of a rectangular member pivotally mounted on said fixed member and bobbin carrier on the second member, the pivotal axis of the second member being at right angles to the axis of the bobbin carrier. 65

In testimony whereof we affix our signatures.

THOMAS WILSON.
ARCHIBALD WILSON.
